CHAIR

Francis M. Kelly, Gardner, Mass.

Application May 26, 1955, Serial No. 36,230

Term of patent 7 years

(Cl. D15—1)

FIG. 1

FIG. 2

FIG. 3

Fig. 1 is a front elevational view of a chair, showing my new design;

Fig. 2 is a side elevational view thereof; and

Fig. 3 is a rear view.

The opposite side of the chair from that shown in Fig. 2 is the same as that shown.

I claim:

The ornamental design for a chair, as shown and described.
